UNITED STATES PATENT OFFICE.

RUDOLF BERG, OF PITTSBURG, PENNSYLVANIA, ASSIGNOR OF ONE-HALF
TO FERDINAND WENIG, OF SAME PLACE.

AIR COMPRESSING AND COOLING APPARATUS.

SPECIFICATION forming part of Letters Patent No. 626,883, dated June 13, 1899.

Application filed March 24, 1898. Serial No. 674,992. (No model.)

To all whom it may concern:

Be it known that I, RUDOLF BERG, a citizen of the Empire of Germany, residing at Pittsburgh, in the county of Allegheny and State of Pennsylvania, have invented new and useful Air Compressing and Cooling Apparatus, of which the following is a specification.

My invention relates to certain new and useful improvements in air compressing and cooling apparatus.

The object of my invention is to construct an apparatus of this class which will absorb the heat of the air while the same is being compressed.

My invention particularly relates to an air compressing and cooling apparatus in which the heat of the air is rendered sensible at the stage of its compression and is absorbed by means of a series of disks or heat-absorbers suitably arranged therein, thereby cooling the air.

My invention further relates in providing an air compressing and cooling apparatus of this class with means whereby a series of disks or heat-absorbers are cooled by a continuous flow of water.

My invention further relates in providing an apparatus of this class with a compression-chamber having arranged therein a piston at its lower end to agitate and force the water around and between the series of disks or heat-collectors, which are arranged in the enlarged upper portion thereof.

To make the object of my invention clear, I will state that when the air or gas is compressed the heat contained therein is rendered sensible; or, in other words, the temperature increases and so does the caloric intensity in the compression-chamber. To overcome this increased temperature or to absorb the heat or to cool the air while in the act of compression, I provide the compression-chamber with a series of disks or heat-absorbers, which are suitably arranged therein for the purpose of collecting or absorbing the heat rendered sensible during the stage of compression. These disks or heat-absorbers also divide the air into small parts, so the same will be thoroughly cooled while passing between them. Owing to the continual flow

of water over the disks or heat-absorbers the same are always kept cool, and the absorbing of heat from the compressed air is readily obtained thereby.

My invention further relates in constructing an apparatus of this character which will compress the air, cool the same while compressing, and also expand the same simultaneously.

Briefly described, my invention consists of a compression chamber or cylinder, a piston operating therein, a series of disks or heat-absorbers arranged in the compression chamber or cylinder, an expansion-chamber suitably connected thereto, and suitable operating means therefor.

My invention finally consists in the novel combination and arrangement of parts hereinafter more fully and specifically described, and particularly pointed out in the claims hereunto appended.

In describing the invention in detail reference is had to the accompanying drawings, forming a part of this specification, wherein like letters of reference indicate corresponding parts throughout the several views thereof, and in which—

Figure 1 is a vertical sectional view of my improved air compressing and cooling apparatus, an expansion machine or chamber connected thereto. Fig. 2 is a longitudinal sectional view of a modified form of compressing and cooling apparatus. Fig. 3 is a vertical sectional view of a modified form of an air compressing and cooling apparatus with a single-acting compression chamber or cylinder. Fig. 4 is a cross-sectional view of a modified form of an air-compressing and cooling apparatus. Fig. 5 is a cross-sectional view of a modified form of an air compressing and cooling apparatus with expansion chamber connected thereto.

Referring to the drawings by reference letters, A indicates the casing of the air compressing and cooling apparatus, and B the casing of the expansion-chambers, the same being suitably connected by the air-outlet pipe D. Arranged in the lower portion of the casing A are compression-chambers a' and a'' , within which is placed the water, and

mounted in the enlarged portion of the casing Λ , as at Λ' and Λ^2 , are the disks or heat-absorbers to cool the air while being compressed. These disks or heat-absorbers consist of a series of disks A^8 , which are suitably secured to the rods A^9 , and they have formed integral on one side thereof the lugs or extensions A^{10} , which are adapted to suitably space apart the disks to allow the air and water to pass between the same into the discharge-chamber a^6 .

The rod A^9 may be secured to the sides of the casing Λ in any suitable manner; but I show in Fig. 2 the sides thereof apertured to receive the rods or screw-threaded collars surrounding this apertured portion.

For forcing the water upon the disks or heat-absorbers A^8 after it enters the chambers a' and a^2 I provide the piston P' , having a piston-rod P^{10} , the piston operating in the lower portion of the chambers a' and a^2 , as shown in Fig. 1.

A^4 and A^5 are suction-valves used for the admission of air to the chambers a' and a^2 , which is forced, in connection with the water, by means of the piston P' , up and around the disks A^8 , and thence through the outlet-valves A^6 and A^7 into a discharge-chamber a^6 . From there it is conducted by means of an outlet-

30 pipe D to the expansion-chamber. a^3 indicates an air-inlet pipe for the admission of air to the suction-chamber a^5 . From there it is taken by means of the suction-valves A^4 and A^5 , as heretofore stated, into the chambers a' and a^2 .

a^4 indicates the water-inlet pipe, and d the outlet-pipe which is connected to the regulating-valve C . This regulating-valve consists of a water-chamber c , formed by the casing c' ; the supporting-guideways c^8 , which are formed integral with one side of the casing; the valve c^4 , formed in the lower part of the support or guide c^8 ; the float-valve c^2 , operating in the guide or support c^8 ; the float c^3 , carried by the valve c^2 ; the discharge-opening c^7 , which admits the water into the discharge-chamber c^5 , and the outlet-pipe c^6 . It is readily apparent that by the use of this regulating-valve C a continuous flow of water from the discharge-chamber a^6 is obtained. The operation of this valve can be readily understood.

The suction-valves are operated by the levers F and F' , which are connected by the pitman-rod E' , carrying the eccentric E , which is operated by the shaft H and which is suitably secured thereto.

K indicates a crank, and J a crank-pin.

It will be readily observed that as the eccentric operates the pitman-rod E' the lever F' , which is connected thereto and which is secured to the shaft carrying the lever F , the suction-valves are operated alternately. No further description of its operation is thought necessary, as the drawings clearly show these parts, so the operation can be readily understood therefrom. It will also be readily ob-

served that owing to the connection of the crank K by the crank-pin J to the piston-rod the same are operated simultaneously.

The expansion machine or chambers B consist of a casing, as shown, having the air-inlets b' and b^2 and outlets b^3 and b^4 , having suitable valves mounted therein, as shown. These valves are of the Corliss type, and, owing to their construction and the pressure of the air in the inlet and outlet passages, the regulation of the air passing therethrough is readily obtained.

Figs. 2 and 3 show a modified form of my improved air compressing and cooling apparatus with a single compression-chamber and heat-collecting device, the same reference-letters being applied to the several parts thereof.

Fig. 4 is a modified form of differential air-compressor, same reference-letters being applied to the several parts thereof.

Fig. 5 shows a modified form of air compressing and cooling apparatus with a single compression-chamber and a modified form of expansion-chamber with suitable valves and operating mechanism B therefor. The valve operating the mechanism in connection with this modified form of air compressing and cooling apparatus consists of a supply-valve B' and exhaust-valve B^2 , which are operated by the levers B^3 and B^4 , secured to the shaft B^5 . These levers are operated by the connecting-rod, which is secured to the eccentric, as heretofore stated. It will be readily observed that owing to the lever B^3 having a pair of operating-arms and which operates upon the springs B^6 and B^7 the valves are operated alternately.

b' indicates the air-inlet; b^2 , the air-receiving chamber; b^3 , the expansion-chamber; b^4 , the exhaust-chamber; and b^5 the outlet therefor.

G indicates a steam-cylinder, G' the inlet for the steam, and G^2 the outlet. P^3 is a piston operating in the cylinder, and G^2 the piston-rod. These parts are of any ordinary construction.

The operation of my improved air compressing and cooling apparatus is as follows: When the shaft is operated by means of the pulley G , carrying the belt G' , which is connected to the shaft H , the water T in the chambers a' and a^2 is agitated and forced in the enlarged portions a' and a^2 , thereby cooling the disks or heat-absorbers A^8 contained therein, and in turn the air is admitted into these chambers, where it is compressed, and during this process of compression the heat contained therein is absorbed by the disks or heat-absorbers A^8 . From there it is conducted into the expansion-chamber by means of the pipe D , where it is expanded.

It will be readily apparent that the operation of the suction-valves is simultaneous with that of the piston in the chambers a' and a^2 and the expansion-chambers. It will also be readily observed that the water after it enters the discharge-chamber will pass into

the discharge-pipe d , and thence outwardly through the regulating-valves C therefor.

It will be noted that various changes may be made in the details of construction without departing from the general spirit of my invention.

Having thus fully described my invention, what I claim as new, and desire to secure by Letters Patent, is—

10 1. In an apparatus of the class described, the combination of a compression-chamber and a piston operating therein; rods suitably mounted in the walls of said compression-chamber and a series of heat-absorbing disks 15 mounted upon and suitably spaced apart on said rods; an air-chamber and suction-valves operating therein; a discharge-chamber and valves connecting said discharge-chamber with the compression-chamber; an expansion-20 chamber and a pipe connecting said expansion-chamber with the discharge-chamber; a piston operating in said expansion-chamber; means for operating the pistons and connections between the operating means of the 25 pistons and the suction-valves of the air-chamber whereby said valves are operated simultaneously with the operating of the pistons, substantially as described.

2. In an air compressing and cooling apparatus, the combination of a compression-chamber, an expansion-chamber and a discharge-chamber communicating with said expansion-chamber, a series of disks or heat-absorbers mounted within the compression-chamber and 35 suitably spaced apart, said expansion-chamber having suitable inlet and outlet passages, valves arranged in said passages; an air-chamber, a pair of suction-valves operating therein, and means for alternately operating 40 said valves, substantially as described.

3. In an air compressing and cooling apparatus, the combination of a compression-chamber, a series of disks or heat-absorbers mounted in said compression-chamber and adapted 45 to cool the air during compression, a piston operating in said chamber, an air-chamber, suction-valves controlling the inlet and outlet passages of said air-chamber, a pipe connecting said discharge-chamber and the ex-

pansion-chamber, a piston operating in said expansion-chamber, and means whereby the piston in the compression-chamber, the piston in the expansion-chamber and the suction-valves controlling the inlet and outlet passages of the air-chamber are operated simultaneously, substantially as described. 55

4. In an air compressing and cooling apparatus, the combination of a compression-chamber and a piston operating therein; a series of heat-absorbers mounted in said compression-chamber and adapted to cool the air during its compression; an expansion-chamber and a piston operating therein; a pipe connecting said expansion and compression chambers, a drive-shaft, connections between 60 the piston of the expansion-chamber and the piston of the compression-chamber; an air-chamber and a pair of suction-valves controlling the inlet and outlet passages of said chamber, and a rod eccentrically connected 65 at its one end to the drive-shaft and at its other end connected by levers to the suction-valves whereby the same are alternately operated and in conjunction with the operating of the pistons in the compression and expansion chambers, substantially as described. 70

5. In a device for compressing air and cooling the same during compression, the combination of a compression-chamber and a piston operating therein; an expansion-chamber and a piston operating therein; a series of heat-absorbing disks mounted within the compression-chamber and suitably spaced apart; a discharge-chamber and a pair of suction-valves connecting said discharge-chamber with the compression-chamber; a regulating-valve suitably supported and communicating with the discharge-chamber, a drive-shaft, and means operated by said drive-shaft for simultaneously operating the 80 pistons and the suction-valves, substantially as described. 85

In testimony whereof I affix my signature in presence of two witnesses.
